UNITED STATES PATENT OFFICE.

FRANK V. COWAN, OF CHICAGO, ILLINOIS.

DESIGN FOR AN AUTOMOBILE-METER.

50,568.

Specification for Design.

Patented Apr. 10, 1917.

Application filed November 27, 1916. Serial No. 133,791. Term of patent 7 years.

To all whom it may concern:

Be it known that I, FRANK V. COWAN, a citizen of the United States, and a resident of Chicago, county of Cook, and State of Illinois, have invented a new, original, and ornamental Design for Automobile-Meters, of which the following is a specification, reference being had to the accompanying drawing, forming a part thereof.

In the drawing, Figures 1, 2 and 3 are

respectively a front view, a side view, and a back view, of the automobile meter embodying my new design.

I claim:

The ornamental design for an automobile meter, substantially as shown.

FRANK V. COWAN.
